UNITED STATES PATENT OFFICE.

LOUIS P. MOOERS, OF CINCINNATI, OHIO, ASSIGNOR, BY DIRECT AND MESNE ASSIGNMENTS, TO THE CLEVELAND TRUST COMPANY, OF CLEVELAND, OHIO, A CORPORATION OF OHIO.

PISTON FOR INTERNAL-COMBUSTION MOTORS.

1,402,308.

Specification of Letters Patent.

Patented Jan. 3, 1922.

Application filed June 28, 1916, Serial No. 106,503. Renewed June 21, 1920. Serial No. 390,623.

To all whom it may concern:

Be it known that I, Louis P. Mooers, a citizen of the United States, residing at Cincinnati, in the county of Hamilton and State 5 of Ohio, have invented certain new and useful Improvements in and Relating to Pistons for Internal-Combustion Motors, of which the following is a specification.

This invention relates to pistons for use 10 particularly in internal combustion motors.

One of the objects of my invention is to produce a simple, light, durable and efficient skirted piston peculiarly adapted to meet the conditions which exist within an 15 internal combustion motor cylinder, including the stresses and strains imposed upon the piston, principally during the explosion stroke and by the high heat generated at this time, which heat must be efficiently and 20 economically (a) utilized in the translation of heat into mechanical energy and (b) that not translated, into mechanical energy properly dissipated.

My present invention comprises improvements 25 on the joint invention of Edward O. Spillman and myself, disclosed in Letters Patent of the United States No. 1,092,870. It contemplates simplifying the construction and manufacture of pistons of this patented 30 type by making them in two or more parts, if desired of different materials, and of considerably lightening the construction as compared with the integral cast structure illustrated in the said patent.

35 Purely for the purposes of disclosure herein I have selected to illustrate and describe one construction of internal combustion motor, skirted piston and a modification thereof embodying my improvements.

40 In the drawings, Fig. 1 is a side elevation of a piston embodying my improvements.

Fig. 2 is a section on the line 2—2, Fig. 1.

Fig. 3 is a section on the line 3—3, Fig. 2.

45 Fig. 4 is a bottom plan view.

1 is the skirt, body or guide portion of the piston, which may be made of a section of steel tubing or a steel stamping having diametrically opposed apertures through it, 50 1^a, 1^b, concentric with the axis of the wrist pin bosses, to permit the insertion and withdrawal of the wrist pin, in the well known manner, as desired. The section 1 may be

drawn or stamped so close in external diameter to the internal diameter of the cylinder walls with which it is adapted to contact and co-operate, that it should not be necessary to machine this section or guide portion of the piston, although it will be understood that if desired it may be machined or treated in any preferred mechanical manner.

3 indicates as an entirety a combined top or piston head and connector. It comprises an end wall 3', an outer peripheral wall 3^a 65 formed preferably with suitable piston ring grooves 3^b, and a downwardly or inwardly extending annular section 3^c. This annular section 3^c is expanded at its lower end to have a tubular section 3^d, the outer wall of 70 which engages with the inner wall of the skirt 1 near the bottom of the latter. Intermediate its ends the section 3^c is preferably formed with diametrically opposed aligned annular wrist pin bosses 3^e, 3^{e'}, one of which 75 may have a downwardly or inwardly extending lug 3^f formed with a screw-threaded opening to receive in the well known manner a suitable locking bolt or screw for the wrist pin. The periphery of the section 3^d may 80 be recessed, as indicated, at 3^g to provide drainage ducts for the lubricant which may collect between the skirt 1 and the lower end of the tie part 3^c. Where I make the skirt 1 of a section of steel tubing, if the combined piston head and tie piece 3 is made 85 of an iron or steel casting, the connection between its lower end 3^d and the skirt 1 may be made in any suitable manner as by spot welding.

90 A piston of my improved construction may be made unusually light, durable and efficient by having the skirt 1 a section of steel tubing and the combined head and connector a casting of metallic alloy having relatively low specific gravity, such for example as a suitable aluminum alloy. Furthermore, the casting for the part 3 may be not only of metallic alloy having relatively low specific gravity, but also possessing a high coefficient 95 of heat conductivity, in which instance the heat necessarily dissipated by the piston will be efficiently dissipated by the web or tie piece 3^c so as to insure that the skirt 1 will be maintained at a relatively low temperature 100 under all normal working conditions.

Where the casting for the combined head and tie piece 3 is made of a metallic alloy having a relatively low specific gravity and high coefficient of heat conductivity, such as 5 an aluminum alloy, the connection between its lower end 3^a and the adjacent wall of the skirt 1 may be made in any suitable mechanical manner, as for example by rivets 10 4, counter-sunk in the sleeve 1, as indicated in dotted lines in Figs. 2 and 4.

It will be understood that the sleeve or skirt 1 may be constructed so as snugly to fit the inner walls of the motor cylinder, whereas the head 3' may be given a considerable amount of clearance between its outer periphery and the inner wall of the cylinder to allow for all necessary expansion of the head due to the high temperatures to which it is subjected. The heat absorbed by 15 20 the head is transferred downwardly by the connecting piece 3^c to the lower end of the skirt 1, and much of it is dissipated by radiation, so that the skirt is kept relatively cool and may be readily lubricated to provide and 25 maintain the proper working relationship between it and the inner wall of the motor cylinder with which it co-acts. The fit between the skirt and the inner wall of the cylinder, as before indicated, may be a snug 30 35 40 45 50 55 60 65 70 75 80 85 90 95 100 105 110 115 120 125 130 sliding fit, and the area of the skirt which co-acts with the inner wall of the motor cylinder is such as to insure against slapping or rapping of the piston against the inner wall of the cylinder. In fact, objectionable so-called piston slap, incident to the operation of numerous types of pistons for use in internal combustion motors, substantially is eliminated by the use of a piston constructed in accordance with my invention. Furthermore, a piston embodying my improvements herein described practically eliminates so-called "oil pumping" or transfer of an undue amount of oil or lubricant from the crank case to the upper end of the piston, resulting in undesirable smoking and undue and troublesome carbonization, among other things.

Due to the fact that the sleeve or skirt is maintained relatively cool under all normal working conditions, the possibilities of scoring of the inner walls of the cylinder are practically eliminated.

The upper end of the skirt 1 is separated from the head 3 by an air gap. The presence of this air gap or air space between the upper edge of the skirt or body section 1 and the lower edge of the peripheral portion 3^a of the piston head, insures that the heat absorbed by the piston head principally will be transmitted inwardly and downwardly so that such portion of it as does reach the skirt or body by convection will do so at the lower end of the skirt and will not be sufficient in amount to cause the necessary expansion of the skirt to effect binding between

the skirt and inner wall of the cylinder or scoring. It will be understood that my invention contemplates any sort of a separated relationship between the upper end of the skirt and the adjacent head 3 because of which heat will not be transmitted efficiently or readily from said head to the skirt. It will be understood that this relationship might be that even of a poor mechanical fit or joint which would be a poor conductor of heat.

It will be noted that my composite piston may be made relatively light in weight, which is of material advantage in assisting in reducing the weight of the reciprocating parts of the motor.

Pistons of my improved construction will be found to operate comparatively noiselessly, smoothly and efficiently within the cylinders of internal combustion motors.

To those skilled in the art, many modifications of and widely differing embodiments and applications of my invention will suggest themselves, without departing from the spirit and scope thereof. My disclosures and the descriptions herein are purely illustrative and are not intended to be in any sense limiting.

What I claim is:

1. A composite piston for an internal combustion motor, comprising a head having an annular, grooved, piston ring carrying flange and a connector extending downwardly from said head and provided intermediate its ends with aligned wrist pin bosses, said head and connector being cast integrally of an aluminum alloy, and a sheet iron guide section into which said connector extends and to the lower end of which the lower end of said connector is secured, there being a relatively small air gap between the upper end of said guide section and the adjacent edge of said head.

2. A composite piston for an internal combustion motor, comprising a head externally grooved to carry piston rings and a connector extending downwardly from said head and having formed intermediate its ends a pair of aligned wrist pin bosses, said head and connector being cast integrally of a metallic alloy having a lower specific gravity than iron, and a sheet iron guide section into which said connector extends and to the lower end of which the lower end of said connector is secured, there being a relatively small air gap between the upper end of said guide section and the adjacent edge of said head.

3. A composite piston for an internal combustion motor, comprising a head, wrist pin bosses, a web between said head and bosses and an extension below said bosses cast integrally, and a separately formed wear-resisting guide section shaped snugly to fit the inner walls of the motor cylinder

and secured to said extension of said casting below said wrist pin bosses therein.

4. A composite piston for an internal combustion motor, comprising a head, wrist pin bosses, a web between said head and bosses and an extension below said bosses cast integrally of a metallic alloy having a lower specific gravity than iron, and an iron guide section shaped snugly to fit the inner 10 walls of the motor cylinder and secured to said extension of said casting below the wrist pin bosses therein.

5. A composite piston for an internal combustion motor, comprising a head, wrist pin bosses, a web between said head and bosses and an extension below said bosses cast integrally of a metallic alloy having a lower specific gravity than iron, and a guide section of iron connected below said wrist pin 20 bosses to said extension on the casting and having its upper edge separated from the adjacent wall of the head by a relatively poor heat conducting air gap.

6. A composite piston for an internal combustion motor, comprising a head, wrist pin bosses, a web between said head and bosses and an extension below said bosses cast integrally of a metallic alloy having a lower specific gravity than iron, and a sheet metal 30 guide section secured below said wrist pin bosses to said extension on the casting and having its upper edge separated from the adjacent wall of the head by an air gap.

7. A composite piston for an internal combustion motor, comprising a head, aligned wrist pin bosses, a connecting web between the head and the bosses and an annular extension below the bosses cast integrally of a metallic alloy having relatively low specific 40 gravity and shaped to fit relatively loosely within the inner walls of the motor cylinder, and an iron wear-resisting guide section adapted snugly to fit the inner walls of the motor cylinder and secured to said annular extension beneath said wrist pin bosses.

8. A piston comprising a head member, having an active end and an axially extended portion of smaller diameter than the active end and extended to a distance 50 therefrom; and a skirted cross head member formed independently of the head member and comprising a skirt portion overlying the axially extended smaller portion of the head portion, and radially distanced therefrom, and means for attaching said cross head member to the head member at a point distant from the active end of the head portion.

9. A piston comprising a head section having an active end and an axially extended portion of smaller diameter than the active end and extended to a distance therefrom, said axially extended portion carrying means for receiving a wrist pin; a skirted cross head member formed independently of 60 the head member and comprising a skirt

portion overlying the axially extended smaller portion of the head member and the wrist pin receiving portions, said skirt portion being perforated opposite the wrist pin receiving portion; and means for attaching said cross head member to the head member at a point distant from the active end of the head portion. 70

10. A composite piston for an internal combustion motor, comprising a head member, wrist pin bosses, means connecting said head member and wrist pin bosses and an extension below said bosses cast integrally of a metallic alloy having a lower specific 75 gravity and higher coefficient of heat conductivity than iron, and a wear resisting guide section formed of a metal having a greater degree of hardness than said head connected to said casting and having its upper edge separated from said head by a relatively poor heat conducting air gap and its lower edge disposed at a point below said wrist pin bosses. 80

11. A piston comprising a head member having an active end, aligned wrist pin 90 bosses and connections between said head and wrist pin bosses cast integrally, a guide portion formed independently of said casting and comprising wear resisting surfaces adapted in normal operation to engage the 95 walls of the engine cylinder, and means for attaching said guide portion to said casting at a point distant from the active end of the head member.

12. A piston for internal combustion engines formed in two parts, one of which is made of metallic alloy having a lower specific gravity and higher coefficient of heat conductivity than iron and comprises a head portion, wrist pin bosses and an extension 100 beneath said bosses, and the other of which parts is made of a metal of greater degree of hardness and greater wear resisting characteristics for rubbing contact with the cylinder walls than said first described part, 105 and means for attaching said parts together at a point distant from the active end of the head portion. 110

13. A composite piston for an internal combustion motor, comprising a head, wrist 115 pin bosses and connecting parts between said head and bosses cast integrally of a metallic alloy having a lower specific gravity than iron, and a guide section of iron attached to said connecting parts and having 120 its upper edge parts separated from the adjacent wall of the head by an air gap.

14. A composite piston for an internal combustion motor, comprising a head, wrist pin bosses and connecting parts between 125 said head and bosses cast integrally of a metallic alloy having a low specific gravity in comparison with iron, and a cylinder-engaging guide section of iron connected to said alloy casting with a poor heat-con- 130

ducting air gap provided between the upper part of the guide section and the lower part of the head.

15. A composite piston for an internal combustion engine comprising a head, wrist pin bosses and connections between said head and bosses cast integrally of a metallic alloy having a lower specific gravity and higher coefficient of heat conductivity than iron, and a guide section of iron connected

to said casting at a point distant from the active end of the head and having its upper edge separated from said head by a relatively poor heat conducting air gap.

In testimony whereof I affix my signature, 15 in the presence of two witnesses.

LOUIS P. MOOERS.
